US00D873421S

(12) **United States Design Patent** (10) **Patent No.:** **US D873,421 S**
(45) **Date of Patent:** **** Jan. 21, 2020**

(54) **FINGER SHIELD**

(71) Applicant: **Med et al., Inc.**, Matthews, NC (US)

(72) Inventor: **David Zilber**, Matthews, NC (US)

(73) Assignee: **MED ET AL.**, Matthews, NC (US)

(**) Term: **15 Years**

(21) Appl. No.: **29/621,955**

(22) Filed: **Oct. 12, 2017**

(51) **LOC (12) Cl.** **24-01**

(52) **U.S. Cl.**

USPC **D24/190**; D29/114

(58) **Field of Classification Search**

USPC D24/188, 190; D29/113–117.2

CPC A41D 13/087; A41D 19/00; A41D

19/01588; A63B 71/148; A61F 5/0118;

A61F 5/05875

(57) **CLAIM**

The ornamental design for a finger shield, as shown and described.

DESCRIPTION

FIG. 1 is a top perspective view of the finger shield showing the new design;

FIG. 2 is a top perspective view of the finger shield rotated relative to FIG. 1;

FIG. 3 is a bottom perspective view of the finger shield;

FIG. 4 is an elevational view of an end of the finger shield, the opposing end view being identical;

FIG. 5 is an elevational view of a side of the finger shield, the opposing side view being identical;

FIG. 6 is a top plan view of the finger shield;

FIG. 7 is a bottom plan view of the finger shield;

FIG. 8 is an elevational view of a side of the finger shield on a hand of a user; and,

FIG. 9 is a perspective view of an end of the finger shield on a hand of a user.

The broken lines shown herein depict environmental subject matter only and form no part of the claimed design.

1 Claim, 9 Drawing Sheets
